UNITED STATES PATENT OFFICE

2,638,808

LEVER ACTUATED SLIDABLE JAW WRENCH

Ben E. Arnold, Port Orchard, Wash.

Application December 13, 1951, Serial No. 261,403

1 Claim. (Cl. 81—126)

1

This invention relates to a tool, and more particularly to a manually operable, adjustable wrench for handling nuts, pipes, or other objects.

The object of the invention is to provide an adjustable wrench which includes jaws that are adapted to be locked onto a nut, pipe or other object, whereby upon application of pressure to the wrench handle, the object can be rotated or moved.

Another object of the invention is to provide an adjustable wrench which includes jaws that can be adjusted to engage a nut or the like, so that the wrench can be readily and quickly adjusted to fit various sizes of objects, the wrench being readily locked and unlocked by simple manual movement.

A further object of the invention is to provide an adjustable wrench which is extremely simple and inexpensive to manufacture.

Other objects and advantages will be apparent during the course of the following description.

In the accompanying drawings forming a part of this application, and in which like numerals are used to designate like parts throughout the same;

Figure 1 is a side elevational view of the wrench of the present invention, showing a nut positioned between the jaws;

Figure 2 is a top plan view of the assembly shown in Figure 1; portions being shown in cross-section;

Figure 3 is a sectional view taken on the line 3—3 of Figure 2.

Referring in detail to the drawings, the numeral 10 designates a first jaw which can be made of any suitable material, such as a suitable metal, and the jaw 10 includes a work-engaging portion 11 and a portion 12, the portions 11 and 12 being arranged at right angles with respect to each other so that the jaw 10 as a whole has a substantial L-shape. A second jaw 14 is provided which includes a work-engaging portion 15, and extending at right angles thereto is a pair of spaced, parallel guide plates 16 and 17. The guide plates 16 and 17 are spaced apart so that they slidably straddle the portion 11 of the jaw 10. The plates 16 and 17 are provided with an elongated, longitudinally extending slot 18, Figure 3. A pin 20 extends through the registering slot 18, and also through the section 11 of the jaw 10 for a purpose to be later described.

The adjustable wrench of the present invention further includes an elongated handle 21 which may be made of any suitable material, the handle 21 being provided with a bifurcated end

2

22 through which projects the portion 12 of the jaw 10 and between which the jaw 14 is pivoted by pin 23. The handle 21 is also provided with an inclined face 24 for a purpose to be later described.

In Figures 1 and 2 there are shown two objects which may be plates, and the objects are indicated by the numerals 25 and 26. A bolt 27 may extend through registering openings in the members 25 and 26, and a nut 28 may be arranged in threaded engagement with the bolt 27. Thus, the adjustable wrench of the present invention may be used for removing the nut 28 from the bolt 27, or it can be used for placing the nut 28 on the bolt 27, so that the pieces 25 and 26 can either be separated or locked together.

From the foregoing, it is apparent that an adjustable wrench has been provided which operates on a wedge-locking principle. The wrench is simple and inexpensive to manufacture, and is easy to adjust, requiring only a simple movement of the finger. Also, the wrench can be adjusted to accommodate various sizes, since the span of the jaws can be regulated or adjusted. Also, no screws or nuts need to be turned in order to adjust the wrench. To adjust the wrench jaws, the jaw 10 is manually moved so that it engages the opposite side of the nut 28 from that of the jaw 14. This movement is permitted due to the sliding of the rivet or pin 20 in the slot 18. Also, at the same time, the portion 12 of the jaw 10 will move upwardly through the bifurcated end of the handle 21 until the nut 28 is engaged by both jaws. Then, a slight downward movement is exerted on the handle 21 so that the inclined face 24 of the handle 21 engages the portion 12 of the jaw 10. This effects the wedging action between the inclined face 24 and the portion 12 of the jaw 10. Also, the slight movement forward of the section 12 of the jaw 10 effects a wedging action between the section 12 and the rear faces of the jaw 15. In other words, the end of the portion 12 is tightly gripped or pinched between the jaw 15 and the face 24 by the downward movement of the handle. Then, to rotate an object, such as the nut 28, the user merely continues to apply pressure on the handle 21 in the same direction that was used to lock the wrench. When it is desired to unlock the wrench, the user merely applies a reverse application of the pressure to the handle 21 so that the wrench will be unlocked.

What is claimed is:

In a wrench of the character described comprising an L-shaped fixed jaw, a second L-

shaped jaw slidably secured to the said first-mentioned jaw and in confronting relation thereto, a handle having a bifurcated end pivotally secured to said first mentioned jaw, said bifurcated end surrounding the secured right angular leg of second mentioned jaw whereby pivotal movement of said handle in one direction will effect a gripping action between the confronting portions of said jaws.
